UNITED STATES PATENT OFFICE.

JAMES A. CAMERON AND GUSTAF BIRGER BIRCH, OF BROOKLYN, NEW YORK,
ASSIGNORS TO CAMERON MACHINE COMPANY, OF BROOKLYN, NEW YORK, A
CORPORATION OF NEW YORK.

SLITTING AND REWINDING MACHINE.

Application filed December 6, 1917, Serial No. 205,840. Renewed January 13, 1922. Serial No. 529,088.

To all whom it may concern:

Be it known that we, JAMES A. CAMERON and GUSTAF B. BIRCH, citizens of the United States, and residents of the borough of Brooklyn, in the city of New York, county of Kings, and State of New York, have invented certain new and useful Improvements in Slitting and Rewinding Machines, of which the following is a specification.

10 The present invention relates to slitting and rewinding machines and more especially to the type employed in paper making mills.

Paper is now manufactured in very wide widths, say from one hundred and twenty to 15 two hundred or more inches, and it has become the custom to slit the paper as it comes from the paper making machinery into rolls of commercial size. The rolls thus produced may, of course, be, and frequently are, still 20 further subdivided into sections of various sizes ranging all the way down to a very narrow width and small diameter of roll, known as "midget rolls", such for instance, as are used for adding machines or automatic telegraphing machines. 25 It has been found in handling rolls of relatively small size, that certain problems are encountered with respect to the slitting and rewinding thereof. These problems have 30 been in a general way set forth in the patent to Cameron & Birch No. 1,076,189 of October 21, 1913.

When, however, it is attempted to slit a very wide web coming fresh from the paper 35 making machinery, a somewhat different set of conditions arise that call for methods different from those employed in overcoming the difficulties encountered in slitters and rewinders of relatively small size. In a very wide 40 web of paper, the difference in thickness at the opposite sides of the web is frequently far more pronounced than a similar difference found in paper coming from commercial rolls that are subdivisions of a large primary roll. Also, the paper being freshly 45 made is, in a measure, still plastic and consequently unless care is taken, rolls fit for commercial use will not be produced. It will also be understood that while it is 50 comparatively easy to control the flow of the web from a commercial roll that is mounted on a supporting shaft in alignment with the

remaining rollers of the machine, it is extremely difficult to align the paper reels and the slitters and rewinders in such way that the flow from the paper reels will be uniform and straight with respect to the rollers of the slitting and rewinding machine. Also, owing to the plasticity of the paper as it comes from the paper making machinery, it is necessary to handle it more delicately and to urge rather than to forcibly control it. There is still one more factor that may be mentioned in this connection and that is the strain and stress placed upon the rollers and drums of the machine when wide widths are being handled because of the great size and weight of the rewound coils.

The main object of this invention is to produce a slitting and rewinding machine 70 that is capable of dealing adequately with the problems above stated and to efficiently and reliably slit and rewind wide sections of paper. One feature of the invention resides in a method and means for spreading 75 the slitted web sections which consists in stretching the unslitted web transversely so as to remove and prevent the formation of longitudinal wrinkles in the web. This stretching is of such character that the 80 width of the web is slightly increased so that when the slitting action takes place, the slit sections will contract to a slight extent thus separating and preventing interweaving of adjacent coils. Also, in connection 85 with this feature, there may be used a secondary separating means that acts to sever any fibers remaining after the slitting operation and also to slightly deflect the side edges of adjacent sections so as to still further separate the slitted sections.

Another feature of the invention resides in a means for compensating for the difference in thickness of opposite sides of the coils when rewinding the web. In machines of 95 this character, when handling freshly made webs, the difference will frequently be so great as to tend to produce a tightly wound coil of large diameter at one end of a rewinding shaft and a comparatively loosely wound coil of smaller diameter at the other end, the thinner edge winding into the coil of small diameter and the thick side winding into the hard coil of greater diameter. Ob-

viously, this difference may change at any time during the winding of the paper since the paper making machinery may be adjusted and the "mushy" end of the roll may be transferred to the other end, etc. In order to compensate for this variation, it has been found that a rewinding device including surface rewinding drums and a riding roller may be effectively used together with means for 10 tilting the rewinding shaft with respect to the plane of its normal axis. Also, if desired, the riding roller may be tilted independently of the rewinding shaft, either in the same or in the opposite direction with respect to the 15 latter. By relieving the weight on the end of the smaller diameter and increasing it on the end having the greater diameter, the winding action of the drums will be most effective on the larger end and least effective 20 on the smaller end so that the paper on the smaller end will wind more loosely and thus tend to restore a uniform diameter of roll.

In the present invention, the rear rewinding drum is preferably driven at a slightly 25 higher rate of speed than the front rewinding drum; and the riding roller is so arranged with relation to its driving mechanism that it may be driven at a higher speed than the rewinding drum or it may be 30 disconnected from its driving means altogether and be used as a retarding roller to effect a drag on the paper. This latter condition is very effective when raising the small end of the roll with respect to the 35 rewinding drums and bringing it more firmly in contact with the riding roll. In these circumstances, it is evident that the thick end of the roller will be wound tighter by the surface rewinding drum while the 40 thin end of the roll will be wound more loosely by being relieved of the pressure against the rewinding drums and by being held more firmly in contact with the idly 45 rotating riding roller; or the riding roller may be tilted with respect to the plane of its own normal axis and with respect to the rewinding shaft.

Another feature of the invention resides 50 in the general organization of the machine, and in the location of the various parts with respect to each other. For instance, the power unit and gearing is on one side of the machine and all of the controlling elements 55 for both the power unit and transmission mechanism and also for the lifting and lowering mechanism of the rewinding shaft and the riding roller, as well as the means for tilting the rewinding shaft, are on the other side of the machine grouped within easy 60 reach of each other.

Another feature of the invention resides in the particular means employed for tilting the rewinding shaft which consists here in a controller shaft having transmission ele-

ments at its opposite ends connected to similar elements on a displaceable rewinding shaft together with means at one end for adjusting the connection between the two shafts while maintaining interconnection between both ends. 70

While certain features of the invention are preferably applicable to a slitting and rewinding machine of the type previously indicated, there are features that are capable of use in ordinary slitting and rewinding 75 machines. These other subsidiary features will further appear as the specification proceeds. 80

The invention is embodied in the accompanying drawings in which:

Figure 1 is a front elevation, looking in the direction of the arrow 1 of Fig. 3 and partly in section and with portions broken away and removed, of a machine embodying 85 the invention.

Figure 2 is a detail sectional view on the line 2, 2, of Fig. 1.

Figure 3 is a side elevation of the machine, looking in the direction of the arrow 3 of Fig. 1. 90

Figure 4 is a vertical transverse section on the line 4, 4, of Figure 1.

Figure 5 is a vertical section on the line 5, 5, of Fig. 1.

Figure 6 is an enlarged sectional view of 95 the slitting means and adjacent elements shown in Fig. 4.

Figure 7 is a plan view of the deflector and separator shown in Fig. 6.

Figure 8 is a vertical sectional view on 100 the line 8, 8, of Fig. 1.

Figure 9 is a vertical sectional view on the line 9, 9, of Fig. 8.

Figure 10 is a sectional view on the line 10, 10, of Fig. 6. 105

Figure 11 is a sectional view through one of the cutters.

Figure 12 is a vertical section on the line 12, 12, of Fig. 5.

Figure 13 is a vertical section on the line 13, 13, of Fig. 5. 110

Figure 14 is a vertical section on the line 14, 14, of Fig. 3.

Figure 15 is a sectional view on the line 15, 15, of Fig. 14. 115

Figure 16 is a plan view of a modification of the parts shown in Fig. 10.

Figure 17 is a front elevation of the elements shown in Fig. 16.

Figure 18 is a section similar to a part of Fig. 6 showing the modifications disclosed to Figs. 16 and 17. 120

Figure 19 is a detail view showing a modification of the deflector and separator shown in Figs. 6 and 7. 125

Figure 20 is a plan view of the stretching means shown in Fig. 4.

Figure 21 is an end view of the transmis-

sion unit looking from the left hand side of Fig. 13.

The invention can best be understood by first locating the main elements involved in the form that it here takes. As illustrated, 1 and 2 indicate front and rear surface rewinding drums rotating in the same direction; and in a plane above and between said drums is a rewinding shaft 3 and, above the latter, a riding roller 4. The slitting means here consist of a score cutter 5 which may engage with any suitable cutter roll, such as one of the rewinding drums, but which, in the present form, acts, independently of the rewinding drums, against a roller other than the rewinding drum,—here a cutter roll 6 provided with a surface harder than that of score cutter 5. The cutter roll 6 preferably consists of a core member, as shown, and an outer sleeve 7 having a glass-hard surface. Whatever may be the character of the element with which the score cutter engages, said element is preferably driven positively and at the same speed at which the web travels. In the present instance, the cutter roll 6 is rotated positively in the same direction as rewinding drums 1 and 2 and at the speed of rewinding drum 1. Preferably, rewinding drum 2 is driven at a slightly higher rate of speed in a manner well understood.

8 indicates a compensating roller for guiding the web into the machine in such manner that it will run substantially at right angles to the axis of the slitting and rewinding elements. 9 is a stretching device for stretching the unslitted web transversely to remove longitudinal wrinkles and also to admit, when the web is slitted, of contraction to normal size of the individual sections of the slitted web. 10 is a tension roller interposed between the stretching and the slitting means. 11 indicates, in a general way, secondary separating means that act on the slitted sections before they are rewound. It will be understood that rewinding shaft 3 and riding roller 4 are automatically displaced in a vertical direction as the diameter of the rewound coils 12 increases; and, to this end, these shafts are carried by suitable slides that work in upright guides on the frame work. Appropriate means, such as a hand wheel 13 and its connections, are provided for lifting and lowering the riding roller at the will of the operator, such means being so arranged that the riding roller is normally parallel to rewinding drums 1 and 2 but means are also provided to alter or destroy this parallel relation at will. Suitable means, such as a hand wheel 14 and its connections, are also provided for manually lifting and lowering rewinding shaft 3 at the will of the operator; and these latter means also include a device, indicated by a hand wheel

15 and connections therefrom, for tilting the rewinding shaft by raising or lowering one end so as to bring it out of parallel relation with the surface rewinding drums 1 and 2 and riding roller 4. It will be understood that while hand wheels 13 and 14 are arranged concentric with respect to each other, they nevertheless control independently the raising and lowering means for the riding roller and for the rewinding shaft. 70 It will also be understood that the tilting of the rewinding shaft by means of hand wheel 15 effects a permanent adjustment of the parts so that thereafter, and until another adjustment is made, said shaft will remain in the position, with respect to its own normal axis, to which it has been adjusted but that said adjustment does not prevent bodily lifting and lowering of the rewinding shaft 3 by means of hand wheel 14. 16 indicates a power unit located at one side of the machine (see Figs. 1 and 12) from which motion for actuating the various elements of the machine is derived. This power unit comprises essentially a 80 motor element denoted by pulley 17, a clutch element 18 for throwing power on and off, and a brake element 19 for bringing the parts to a stop when power ceases to be applied. 20 is a gear that transmits power to the different parts of the machine. This gear is keyed directly to the shaft of rewinding drum 2 and transmits power directly to it, power to the remaining portion 85 of the machine being transmitted by the following means. Adjacent to the power unit is a transmission unit, generally indicated by 21 (see Figs. 1, 12 and 13). This transmission unit receives motion from gear 20 (Fig. 12) of the power unit by reason 90 of the engagement of said gear with an intermediate gear 22. From gear 22 motion is constantly transmitted to a gear 23 on the front rewinding drum 1 and to a gear 24 on cutter roll 6. 25 is a bevel gear by means of which motion is transmitted to a bevel pinion 26 on an upright shaft 27 that drives riding roll 4 by means of bevel gears 28 and 29, the former of which has a splined connection 30 with shaft 27. 100

The above describes, in a general way, substantially all the transmission mechanism necessary for driving the machine and it will be noted that the power unit and the transmission unit are both located on one side of the machine; that the power shaft carrying the gear 20 drives rear rewinding drum 2 directly; that the intermediate gear 22 of the transmission unit is in a plane between and underneath the surface rewinding drums (see Fig. 6); and that said gear 22 is in mesh with the gears of both of the rewinding drums and with the gear on cutter roll 6. 110

The controlling means, consisting of mem- 115

bers 13, 14 and 15, for manually lifting and lowering the rewinding shaft and the riding roll and for tilting the rewinding shaft are all located on that side of the machine which 5 is opposite to that on which the power and transmission units are located (Fig. 1); and, on this same side of the machine, are provided controlling members 31, 32 and 33 (Figs. 1 and 3) which control respectively 10 clutch 18, brake 19 and a rocking member 34 for carrying score cutter 5 into and out of engagement with the cutter roll 6. It will be seen, therefore, that the attendant may control practically all the elements of the 15 machine from one side thereof and this renders its manipulation simple and convenient.

Having now given a general outline of the location of the main elements of the machine and their relation to each other, a detailed description follows: The compensating roll 8 (see Figs. 4 and 8) is a roller that extends transversely of the machine in rear of the surface rewinding drums and at a point above the stretching means 9. Suitable means are provided for tilting this roller with respect to a horizontal axis, taking, in the present instance, the form of an adjustable bearing 35 in threaded engagement with a bracket 36. Such a bearing 30 may be provided at either or both ends of roller 8, as will be understood; and, should the paper coming from the reels of the paper making machine be distorted or travel in a path other than at right angles to the axis of the various rollers of the machine, it may 35 be straightened by adjusting bearing 35 so that it will enter the slitting machine in a proper manner. Also, in case the reels of the paper making machinery and the rollers of 40 the slitting machine should be out of alignment, the compensating roller 8 can be adjusted to correct such defect. This roller is also provided with suitable means that admit of its yielding automatically in a vertical direction at either end and that also admit of the roller being depressed bodily. This compensating roll furthermore serves 45 to equalize the flow of the web being unwound from a parent roll on reels which may not be perfectly cylindrical in shape. In 50 the present instance, these means take the following form. The bearing 35 is hollow, as shown, and is provided with an intermediate abutment member 37. Extending into the bearing 35 is a plunger 38 forming part 55 of the compensating roller carrying means and provided with a reduced portion or stem 39 that extends through abutment member 37. Interposed between abutment member 37 and plunger 38 is a spring 40; and interposed between abutment member 37 and a nut 41 is a second spring 42. It will be understood that if the paper, as it comes 60 from the paper reels, should be so distorted 65 that one side is, in effect, shorter than the

other, the action of plunger 38 against spring 40 will cause one end of compensating roller 8 to yield. On the other hand, should the web snap or break or should the character of the paper suddenly change, undue recoil of compensating roll 8 will be prevented by reason of the cushioning effect of spring 42.

The stretching means 9 are here shown as being located in rear of the surface rewinding drums 1 and 2 and also in rear of, and above, tension roller 10 but below compensating roller 8. This tensioning device may take any form that will admit of its performing the functions for which it is intended,—i. e. mainly to prevent and remove longitudinal wrinkles of the web and to stretch it transversely in such manner that on being slit the sections that are thereby formed will naturally contract transversely, thus separating adjacent sections to prevent subsequent interweaving of adjacent coils when rewound. In the present instance, the stretching means consist of a transversely extending supporting member 43 (see Figs. 4 and 20) to which is secured, at intervals, brackets 44 having adjusted members 45 that carry a stretching bar 46. It will be understood that by adjusting any one of the members 45, the stretching member 46, which is sufficiently flexible for this purpose, may be given various contours to remove longitudinal wrinkles from the paper and to stretch the web, as a whole, in a transverse direction and thereby, in a measure, increase its natural width.

Located in rear of the slitting mean, and below the rewinding drums and the stretching means, is a tension roller 10, of any suitable construction, that serves merely to keep the paper smooth and stretched during its passage to the slitting means. The roller 10 is idle,—i. e., it is not driven by any instrumentality,—and may, under certain conditions, assist in retaining the paper in its smooth and stretched condition by use of a braking element 47 (Fig. 3) exerting a slight tension on the shaft of roller 10. In this way, the tension roller will have sufficient retarding effect on the paper to insure smoothness.

The cutter roll 6 is mounted in a sliding box or bearing 48 (Figs. 5 and 6) and is constantly urged against a backing roller 49 by means of springs 50.

In order to provide the cutter roll 6 with the hardened surface 7, it is necessary to make the roller as small as possible since the difficulty of hardening the material increases as its size increases; and, in order to prevent the tension of the paper on the cutter roll from warping or springing it, it is desirable, when the roll is of small diameter, to provide a backing roll such as 49, that will prevent any deflection of the cutter roll. In

a device in which a score cutter is used for slitting the web, this is of the utmost importance since the paper must at all times lie flat and evenly against the surface of the cutting roll and any deflection out of the plane of severance would unfavorably affect the rewinding of the material. The backing roll 49 is mounted in adjustable bearings so as to permit its withdrawal in case the web should break and the paper accumulate between it and the cutter roll. In the present instance, eccentric bushings 51 are mounted in a bracket 52 (Figs. 4, 6 and 10) so that by turning an operating handle 53, the backing roll 49 may be brought out of engagement with cutter roll 6. As a modification of this structure, a plurality of staggered backing rolls 49' (Figs. 16, 17 and 18) may be used, each backing roll being, as before, mounted in eccentric bushings 51'. It will be seen from Fig. 18, that by this construction the cutter roll is supported in a cradle, as it were, and, in this way, not only will a backward displacement be prevented but also an up-and-down displacement or distortion.

The score cutter 5 bears a peculiar relation to the member with which it engages. In the present instance, the roll 6 is of material harder than that of cutter 5 and is driven positively by means of gear 24, as previously described, at the speed at which the paper is traveling through the slitting means. The score cutter 5 is relatively blunt and is not as hard as the surface 7 of roll 6 which prevents grooves from being formed. Said cutter 5 rotates idly in contact with the positively driven roll 6 and is pivotally supported at 54, being held under considerable tension by means of springs 55, and other means presently to be described, against said cutting roll 6. It will be noted that if a radial line be drawn between the centers of the cutter roll 6 and the pivotal support 54, said line will be in advance, with respect to the direction of rotation of the roller 6, of a similar line drawn between the center of the cutter roll and the center of rotation 56 of the score cutter. The result is that the score cutter has, what may aptly be called, a trailing action with respect to the cutter roll 6, the effect of which is to counter-act any tendency on the part of score cutter 5 to "wobble". This is of the utmost importance in preventing slight inaccuracies in slitting due to minute variation in the parts; and it will be understood that if the arrangement were reversed and the line between the center of roll 6 and the pivotal support 54 should be behind the line between the center of 6 and 56 that no trailing action would take place and consequently any tendency to "wobble" would be increased rather than reduced.

The score cutter and its mounting involve

in themselves new features of construction which are as follows: It will be noted that the score cutters 5 are mounted in front of the machine and constitute substantially the outermost and lowermost elements thereof. It is therefore important that these parts should not project unduly beyond the general outline of the machine. Heretofore it has been customary to have the ends of springs 55 anchored in a stationary member independent of the mounting that carries the score cutter and by means of which it is moved toward and away from the cutter roll. In the construction here disclosed, a very compact and convenient structure is obtained by so arranging the parts that the rocking member 34 that carries the score cutter also forms an abutment against which springs 55 act when the rocking member is turned to bring score cutter 5 into engagement with cutter roll 6. As here shown, this is effected by the following means: 34 indicates the hollow rocking supporting member suitably mounted in the framing of the machine. This member is provided with a guide-way 57 on which are supported sliding brackets 58 of the individual score cutters, said brackets being secured in position by means of set screws 59. A cutter holder 60 is pivotally supported at 54 in bracket 58 and is provided with the rearwardly extending spring 55 adjustably secured by means of a set screw 61 to a projection 62 of bracket 58. It will be seen that when rocking member 34 is turned to the right, in Fig. 6, score cutter 5 will be brought into engagement with cutter roll 6 and that continued movement of the rocking member 34, after contact has been made between 5 and 6, will cause cutter holder 60 to turn on its pivot 54 so as to permit rocking member 34 to continue its movement toward the member 6, thereby lifting the extension 62 and increasing the tension of spring 55.

The score cutter 5 and holder 60 may be of any suitable construction but, in the present instance, they take the following form: The holder 60 is pivotally supported at 54 on bracket 58 and is provided with two upwardly extending arms 63 in which the score cutter itself is mounted. 64 indicates a pin provided with reduced portions 65 that fit into a square slot 66 in arms 63. 67 is an annular cutting member removably secured between the clamping members 68 and projecting outwardly therefrom to form a circumferential cutting member. The two clamping members 68 are suitably secured together as by means of a thread 69. An anti-friction bearing 70 is used in connection with the device. In this manner, the cutting blade 67 may be renewed when required and it is possible to construct the clamping members of the cutter of less expensive material than if the cutting member were of

very large cross section and integral with the parts marked 68. Any suitable means may be utilized for rocking the member 34. In the present instance, the member 34 is 5 provided with an arm 71 (Figs. 1 and 3) bifurcated at its upper end to receive a block 72 through which passes a threaded stem 73 carrying hand wheel 33 and extending at its other end into a stationary bushing 74 on 10 the frame work. By turning the controlling member 33, the threaded stem 73 will move more or less into or out of engagement with a bushing 74 thereby turning the rocking member 34 by engagement of block 72 in the 15 bifurcated member 71. The member 34 is hollow (Figs. 4, 6 and 12) to permit connections to extend from controlling members 31 and 32 to the clutch and brake elements 18 and 19.

20 After the web has been slitted into sections and before said sections are rewound into coils that are axially coincident, it is desirable to run the paper in an unsupported layer for the purpose of effecting a secondary separation of the slitted web sections. If the score cutter acts against the first rewinding drum for the purpose of slitting the material, the paper can then be deflected away from such rewinding drum and back again to 25 obtain the unsupported layer. In the present instance, where the cutter roll 6 is independent of the first rewinding drum 1, this run of the paper in an unsupported layer is naturally obtained as it passes from cutter roll 6 to the first rewinding drum 1. It will be recalled that the paper is stretched before being slit so that upon longitudinal slitting taking place the individual sections thus produced will contract transversely and 30 cause separation between adjacent sections. It happens at times, however, that there may be between adjacent sections a few remaining fibres that have not been severed by the slitting action; and that the paper, in consequence, does not become as distinctly separated as is desirable. For the purpose of 35 remedying this defect, the secondary separating device 11 is provided. In the form as shown (Figs. 6 and 7), this device consists 40 of a supporting member 75 extending transversely of the machine in front of the first rewinding drum. On a shaft 75 is supported a plurality of brackets 76 held in position by means of screws 77. Each of these brackets 45 76 carries a member 78, seated in a socket and held in position by a set screw 79, and consists of a generally ball-shaped member 80 that engages the side edges of the paper of adjacent sections, thus deflecting them 50 slightly and crowding them sidewise to assist in complete separation of said sections. There may also be provided in connection with this deflecting separator, a knife blade 81, which, in the present instance, is shown

as embodied in the member 80, and which 65 serves to sever any remaining threads or fibres between adjacent sections. In the modification shown in Fig. 19, a separating blade 81' is located in advance of the deflecting member 80 and is carried by a downwardly extending arm 82. After the sections are thus completely severed and separated, the paper passes to the rewinding drums and rewinding shaft 3 where it is rewound under the joint action of the two rewinding drums and riding roller 4.

Extending through the hollow rocking member 34 is a sleeve 83 (see Figs. 1, 4, 6 and 12). Secured to one end of this sleeve is a controlling member 31 and secured to the other end is a lever 84 connected to a bell crank 85 pivotally supported at 86 on a standard 87, one end of said bell crank 85 engaging a loose sleeve 88 on a shaft 89 and thereby causing a spiral rack 90 to engage 85 a spiral gear 91 to cause the clamping members 92 keyed to a shaft 89 to engage an intermediate member 93 carried by a driving member 94 keyed to pulley 17 but loose on shaft 89. This clutch is of the type known 90 as the Hilliard clutch and need not be further described.

Extending through sleeve 83 is a shaft 95 secured at one end to the operating member 82 and having, at its opposite end, an arm 96 to the free end of which is secured an upwardly projecting member 97 that engages in a notch on a brake arm 98 pivoted at 99 and provided with a braking element 100 that engages brake pulley 19. This 100 brake pulley 19 is keyed directly to shaft 89.

The transmission unit in its detail construction is as follows (Figs. 1, 12 and 13): The intermediate gear 22 is loosely mounted on a stud 101 and transmits its motion to 105 bevel gear 25 by means of fibre washers 102 having hexagonal openings and carried on an internal bushing 103 of intermediate gear 22. Interposed between the hexagonal washers 102 are iron plates 104 slotted at 110 their outer ends to receive pins 105 carried by bevel gear 25 which latter is likewise mounted loosely on stud 101. In order to exert more or less friction between the hexagonal washers 102 and plates 104, a 115 pressure exerting device 106 is employed. This member 106 is annular in shape and surrounds the internal bushing 103 of intermediate gear 22 and is carried by pins 107 that extend from member 108 rotating with 120 intermediate gear 22 and also capable of a sliding movement on a key 109. Suitable means are provided for effecting this sliding movement of member 108. In this instance, there is a stem 110 engaged in a 125 stationary part of the frame work and provided with two collars 111 between which engages the bifurcated member 112 of rock-

ing member 113 pivotally supported at 114. This rocking member 113 straddles stud 101 and is provided on each side of said stud with a rod 115 (Figs. 4, 12, 13 and 21) 5 which rod 115 is in threaded engagement with a member 116 that is loosely mounted on the hub of intermediate gear 22 so as not to partake of its rotation. The member 116 has interposed between itself and member 108, slip rings, preferably of cast iron, indicated by 117. By adjusting stem 110, one way or the other, more or less pressure will be exerted by the movement of member 116 with relation to member 108 which, in turn, 15 has the effect of bringing the washers and discs 102 and 104 into more or less intimate engagement. By this means, therefore, bevel gear 25 may be driven at a greater or lesser speed, or not at all, as may be desired. To 20 limit the pressure exerted on the friction members just described, a member 118 that carries the pivot 114 for member 113 is carried by a member 119 in the form of a rod sliding in the framing 120 that carries at 25 its outer end the member 118. Interposed between the frame work 120 and nuts 121 is an expansion spring 122. It will be seen that with the pressure of spring 122 set to act at a certain degree, any adjustment 30 above this degree made by means of stem 110 will pull rod 119 through frame 120 instead of turning the member 113 on its pivotal support 114.

The riding roller 4 is mounted in brackets 35 123, of which there is one on each side of the machine, and which are provided with a guide-way 124 embracing a guide 125 (Fig. 2) that forms a part of the uprights 126 on each side of the machine. The gear 40 28 that engages gear 29 of riding roller 4 is likewise carried on bracket 123 and, being splined at 30 to shaft 27, will ride up and down on the latter following the movement of the riding roller but will still 45 impart the motion of shaft 27 to said riding roller. Connecting the brackets 123 is a tie rod 127 so that the riding roller will rise and fall in parallel relation to the rewinding drums. Brackets 123 are suspended by 50 means of chains 128 (Figs. 1, 3 and 4) that pass over an idler sprocket 129 and thence over a sprocket 130 on a shaft 131. Counterweights 132 that slide on tracks 133 of 55 the uprights in the side frame of the machine are attached to the free end of chain 128. It will be understood that the arrangement is in duplicate at opposite sides of the machine. Suitable means for manually raising and lowering the riding roller 4 is provided as follows: Mounted on shaft 131 is a 60 large sprocket 134. Around this sprocket passes a chain 135 that is trained over an idler sprocket 136 and thence passes downward around a sprocket 137 (Figs. 3 and 9)

mounted loosely on a sleeve 138 of a shaft 65 139. Carried by sprocket 137 is a ratchet 140 with which normally engages a pawl 141 to prevent backward rotation. The controlling member 13 is also connected to sprocket 137 and, by rotating said controlling member 13, the train of connections, just described, leading to a shaft 131 will be actuated and riding roller 4 may be elevated or lowered at will. The pawl 141 will be released by means of a treadle 142, or 70 otherwise.

The rewinding shaft 3 is carried in suitable brackets 143 that slide on uprights 126 of the frame work and have secured to them a vertical guide member 144 (Figs. 80 2 and 8) that slides in a guide 145 in uprights 126 and which have projecting rearwardly therefrom blocks 146, 146', one on each side of the machine. On the left hand side of the machine, as in Fig. 1, there is a sprocket chain 147 secured to block 146 and passing around a sprocket 148 keyed to an adjusting shaft 149 (Figs. 3, 4 and 14), said chain 147 thence passing to an idler sprocket 150 mounted on a stud at the left hand side of the machine and thence back to block 146. On the right hand side of the machine, a block 146' is secured to a sprocket chain 147' that passes over a sprocket 148', for normal functional purposes fast on shaft 149. The chain 147' then passes over sprocket 151, thence to a sprocket 150' mounted on the right hand side of the frame work of the machine, and thence back to block 146'. Keyed on shaft 149 is still 90 another sprocket wheel 152 to which is attached a chain 153 carrying at its lower end a counterweight 154. It will be understood that the transmission mechanism just described is interconnected at all times so as to move in unison under the influence of the rising or falling of the rewinding shaft and counterweight 154. Suitable means are provided for manually raising and lowering the rewinding shaft,—in this instance, 100 taking the following form: 14 is a controlling member mounted on shaft 139 to which is secured a pinion 155 (Fig. 9) meshing with gear 156 mounted on stud 157 that also carries sprocket 151. By turning the controlling member 14, motion will be imparted through shaft 139, pinion 155, gear 156, shaft 157 and thence to the transmission mechanism for lifting and lowering the rewinding shaft so that the operator, at will, 105 may raise or lower said shaft. Connected to pinion 155 is also a ratchet 159 with which engages a pawl 160 to prevent backward rotation when the rewinding shaft has been raised. Suitable means, such as connection 161, may be utilized to release pawl 160 from ratchet 159.

Appropriate means are provided for tilt-

ing the rewinding shaft in such manner that it will remain tilted, and will rise or fall bodily without changing its tilted position, with respect to its own normal axis, until 5 another adjustment is made. Loosely mounted on the adjusting shaft 149 is a sleeve 162 to which is keyed sprocket 148'. Keyed to shaft 149 is a sleeve 163. Mounted on sleeves 162 and 163 is an adjusting member 10 164 adapted to impart the rotation of shaft 149 to sprocket 148' or vice versa; and also adapted to permit independent adjustment of sprocket 148' and the chain carried thereby. In the present instance, this is 15 effected by providing sleeve 163 on shaft 149 with a straight slot 165 into which extends a block 166 carried by the adjusting member 164. Formed in sleeve 162 is a spiral groove 167 into which extends a 20 block 168 also carried by the adjusting member 164. If, now, the adjusting member 164 is moved to the right, (Fig. 15), engagement of block 166 with slot 165 will prevent the turning of member 164; and it 25 therefore follows that the loose sleeve 162 will turn on shaft 149 in response to endwise movement of the block 168 in the spiral groove 167 thereby turning sprocket 148' and raising or lowering chain 147' and, consequently, tilting rewinding shaft 3. It will 30 be understood that by moving the member 164 in one direction, the right hand end of by moving the member 164 in the other direction, the right hand end of rewinding shaft 3 will be lowered which, because of 35 counterweight 154, has the effect of raising the left hand end of the rewinding shaft. Suitable means are provided for effecting 40 endwise movement of adjusting member 164,—in this instance, taking the form of a controlling member 15 in threaded engagement with a stem 169 which, by its rotation, will move a pivot lever 170 on its pivotal 45 support 171 and thus, by means of a bifurcated end 172 extending into a groove 173 of the adjusting member 164, produce endwise movement of the latter. It will be observed that rotation of member 164 will not 50 be interfered with in any way by the action of the bifurcated end 172.

Suitable means are provided for tilting the riding roller 4, in this instance taking the form of turnbuckles 200 forming a part 55 of the flexible connection 128. It will be understood that by adjusting one or the other, or both, of the turnbuckles the riding roller may be tilted.

We claim;

60 1. The method of spreading slotted web sections of flexible material which consists in stretching the unslotted web transversely and thereby increasing its natural width, then in restoring the natural width of the material by slitting said web while stretched 65

and thereby permitting the slotted sections to contract individually in a transverse direction, and then in deflecting the side edges of the sections.

2. The method of spreading slotted web 70 sections of flexible material which consists in stretching the unslotted web transversely and thereby increasing its natural width, then in restoring the natural width of the material by slitting said web while stretched 75 and thereby permitting the slotted sections to contract individually in a transverse direction, then in subjecting the slotted sections to the action of a knife while the material is traveling in an unsupported layer, 80 and then in deflecting the side edges of the sections.

3. The method of slitting a web into sections and of rewinding it into coils axially coincident without interweaving which consists in stretching the unslotted web transversely and thereby increasing its natural width, then in restoring the natural width of the material by slitting said web longitudinally while stretched and thereby permitting the slotted sections to contract individually in a transverse direction, then in guiding the slotted sections in an unsupported layer and deflecting the side edges of the sections while traveling in an unsupported 90 layer, and then in rewinding the slotted sections side by side. 95

4. The method of slitting a web into sections and of rewinding it into coils axially coincident without interweaving which consists in stretching the unslotted web transversely and thereby increasing its natural width, then in restoring the natural width of the material by slitting said web longitudinally while stretched and thereby permitting the slotted sections to contract individually in a transverse direction, then in guiding the slotted sections in an unsupported layer, then in severing any remaining threads between adjacent sections while they 100 are traveling in an unsupported layer, then in deflecting the side edges of said sections also while they are traveling in an unsupported layer, and then in rewinding the sections side by side. 110

5. A slitting and rewinding machine comprising: a first and second rewinding drum, a rewinding shaft in a plane above and between the rewinding drums, a cutter roll below the first rewinding drum, a score cutter in front of the cutter roll, and a backing roller behind said cutter roll and below the rewinding drums. 120

6. A slitting and rewinding machine comprising: a first and second surface rewinding drum, a rewinding shaft in a plane above and between the rewinding drums, a cutter roll below the first rewinding drum, a score cutter in front of the cutter roll, separating means above the score cutter and in 125 130

front of the first rewinding drum, and a backing roller behind the cutter roll and below the drums.

7. A slitting and rewinding machine comprising: a first and second rewinding drum, a rewinding shaft in a plane above and between the rewinding drums, a cutter roll below the first rewinding drum, a score cutter in front of the cutter roll, a backing roller

10 behind the cutter roll and below the drums, a tension roller in rear of and below the backing roller, stretching means in rear of the drums and tension roller and above the latter, and a guiding roller above the stretching means and in rear of the drums.

8. A slitting and rewinding machine comprising: a first and second surface rewinding drum, a rewinding shaft in a plane above and between the rewinding drums, a cutter roll below the first rewinding drum, a score cutter in front of the cutter roll, separating means above the score cutter and in front of the first rewinding drum, a backing roller behind the cutter roll and below the drums, a tension roller in rear of and below the backing roller, stretching means in rear of the drums and tension roller and above the latter, and a guiding roller above the stretching means and in rear of the drums.

30 9. In a slitting machine, a cutter roll, a score cutter engaging therewith, a backing roller behind said cutter roll, and eccentric bushings for mounting the backing roller.

10. In a slitting machine, a cutter roll, a score cutter engaging therewith, a plurality of staggered backing rollers engaging with the cutter roll, and adjustable bearings for mounting the backing roller.

40 11. In a slitting machine, a cutter roll, a score cutter co-operating therewith, a sliding bearing for the cutter roll, a backing roller adjacent the cutter roll, a spring normally urging the cutter roll toward the backing roll, and adjustable bearings for the backing roll.

50 12. A slitting and rewinding machine comprising: a first and second surface rewinding drum, a rewinding shaft in a plane above and between the rewinding drums, a cutter roll below the first rewinding drum, a score cutter in front of the cutter roll, a backing roller behind the cutter roll and below the drums, and adjustable bearings for said backing roller.

55 13. A slitting and rewinding machine comprising: a first and second surface rewinding drum, a rewinding shaft in a plane above and between the drums, a cutter roll below the first rewinding drum, a score cutter in front of the cutter roll, a backing roller behind the cutter roll and below the drums, and eccentric bushings mounting the backing roller.

60 14. A slitting and rewinding machine comprising: a first and second surface rewinding

drum, a rewinding shaft in a plane above and between the drums, a cutter roll below the first rewinding drum, a score cutter in front of the cutter roll, a backing roller behind the cutter roll and below the drums, a sliding bearing for the cutter roll, a spring normally urging the cutter roll toward the backing roll, and adjustable bearings for the backing roll.

70 15. A slitting and rewinding machine comprising: a first and second surface rewinding drum, a rewinding shaft in a plane above and between the drums, a cutter roll below the first rewinding drum, a score cutter in front of the cutter roll, a backing roller behind the cutter roll and below the drums, a sliding bearing for the cutter roll, a spring normally urging the cutter roll towards the backing roller, and eccentric bushings for mounting the backing roller.

75 16. A slitting and rewinding machine comprising: slitting and rewinding elements, a power unit including a clutch and a brake located on one side of the machine, controlling means for the elements of the power unit located on the other side of the machine, and connections between the controlling means and the elements of the power units extending through a member forming a part of the slitting means.

80 17. A slitting and rewinding machine comprising: slitting and rewinding elements including a rewinding shaft and a riding roller, a power unit including a clutch and a brake located on one side of the machine, controlling means for the elements of the power unit located on the other side of the machine, and controlling means for raising and lowering the rewinding shaft and riding roller located on the same side of the machine as the first controlling means.

100 18. A slitting and rewinding machine comprising: slitting and rewinding elements including a rewinding shaft and a riding roller, a power unit including a clutch and a brake located on one side of the machine, controlling means for the elements of the power unit located on the other side of the machine, controlling means for raising and lowering the rewinding shaft and riding roller located on the same side of the machine as the first controlling means, means for tilting the rewinding shaft, and operating means for said tilting means located on the same side of the machine as the other controlling means.

110 19. A slitting and rewinding machine comprising: slitting and rewinding elements including a rocking member for causing the slitting means to engage, a power unit including a clutch and a brake located on one side of the machine, controlling means for the elements of the power unit located on the other side of the machine, and shafts extending from said controlling means to the ele-

ments of the power unit extending through the rocking member aforesaid.

20. A slitting and rewinding machine comprising: a first and second rewinding drum, a rewinding shaft in a plane above and between the rewinding drums, a riding roller above the rewinding shaft, a power shaft located in line with the rear rewinding drum and from which the latter is constantly driven, a transmission member intermediate the drums driven at all times from the power shaft, means for driving the front drum from said transmission member at all times, and means for driving the riding roller from the transmission member at variable speeds.

21. A slitting and rewinding machine comprising: a first and second rewinding drum, a rewinding shaft in a plane above and between the rewinding drums, a riding roller above the rewinding shaft, a power shaft located in line with the rear rewinding drum and from which the latter is constantly driven, a transmission member intermediate the drums driven at all times from the power shaft, means for driving the front drum from said transmission member at all times, and a clutch interposed between the intermediate member and the riding roller for driving the riding roller at variable speeds and for disconnecting the riding roller from the intermediate member at will.

22. A rewinding machine comprising: two surface rewinding drums, a displaceable rewinding shaft in a plane above and intermediate the drums, a displaceable riding roller above the rewinding shaft, means for driving the drums and riding roller at different speeds to frictionally engage the coils on the rewinding shaft, and means for tilting the rewinding shaft to vary the winding action of the drums and riding roller at opposite ends of the rewound material.

23. A rewinding machine comprising: two surface rewinding drums, a displaceable rewinding shaft in a plane above and intermediate the drums, a displaceable riding roller above the rewinding shaft, means for driving the drums and riding roller at different speeds to frictionally engage the coils on the rewinding shaft, means for tilting the rewinding shaft to vary the winding action of the drums and riding roller at opposite ends of the rewound material, and means for varying the speed of the riding roller.

24. A rewinding machine comprising: a pair of surface rewinding drums, a rewinding shaft in a plane above and between said rewinding drums, a riding roller above the rewinding shaft, means for driving the drums and the riding roller and thereby frictionally engaging the material to be rewound on the rewinding shaft, and means for disconnecting the riding roller from its

driving means and thereby causing it to act as a retarding means and to be frictionally driven by the rewound material.

25. A rewinding machine comprising: a pair of surface rewinding drums, a rewinding shaft in a plane above and between said rewinding drums, a riding roller above the rewinding shaft, means for driving the drums and the riding roller and thereby frictionally engaging the material to be rewound on the rewinding shaft, means for disconnecting the riding roller from its driving means and thereby causing it to act as a retarding means and to be frictionally driven by the rewound material, and means for tilting the rewinding shaft with respect to the axis of the drums and the riding roller.

26. A rewinding machine comprising: a pair of surface rewinding drums, a rewinding shaft in a plane above and between the rewinding drums, a riding roller above the rewinding shaft, means for manually raising and lowering the riding roller, means for manually raising and lowering the rewinding shaft, and means included in the lifting and lowering means of the rewinding shaft for tilting said shaft with respect to the axis of the rewinding drums and the riding roller.

27. In a rewinding machine, a rewinding shaft, lowering and lifting mechanism at opposite ends of said shaft connected to rise and fall in unison, means for tilting the shaft with respect to the plane of its normal axis consisting of means for adjusting the lowering and lifting mechanism at one end of the shaft while maintaining driving connections between the lowering and lifting mechanism at both ends of the shaft.

28. In a rewinding machine: a controller shaft, a transmission member at each end of the controller shaft connected to rotate in unison therewith, a displaceable shaft, connections from opposite ends of the displaceable shaft to the transmission members of the controller shaft, and means for adjusting one of the transmission members independently of the controller shaft while maintaining driving engagement therewith and thereby tilting the displaceable shaft.

29. In a rewinding machine: a displaceable shaft, a controller shaft, transmission mechanism between the controller shaft and the displaceable shaft, means included in said transmission mechanism for manually actuating the same to lift and lower the displaceable shaft, and means for adjusting the transmission mechanism to lift or lower one end of the displaceable shaft.

30. In a rewinding machine: a displaceable shaft, a controller shaft, transmission mechanism between the controller shaft and the displaceable shaft, means included in

5 said transmission mechanism for manually actuating the same to lift and lower the displaceable shaft, means for adjusting the transmission mechanism to lift or lower one end of the displaceable shaft, and a counter weight for the displaceable shaft connected to the controller shaft.

10 31. In a rewinding machine: a displaceable shaft, a controller shaft, transmission mechanism between the controller shaft and the displaceable shaft at both ends thereof including a member fixed on the counter shaft, a member loose on the counter shaft, a sleeve surrounding both the fixed and 15 loose members and rotatably connected to both, and means for adjusting the loose member by a sliding movement of the sleeve while maintaining driving connection between the fixed and loose members.

20 32. In a rewinding machine, a displaceable shaft, a controller shaft, transmission mechanism between the displaceable shaft and the controller shaft including a member fixed on the shaft and having a straight 25 longitudinal slot, a member loose on the shaft and having a longitudinal spiral slot, a sleeve surrounding both the fixed and loose members and sliding with relation thereto, and blocks carried by said sleeve 30 and extending into said slots whereby endwise movement of the sleeve will adjust the loose member while maintaining driving connection between the fixed and loose members.

35 33. A rewinding machine comprising: two surface rewinding drums, a displaceable rewinding shaft in a plane above and intermediate the drums, a displaceable riding roller above the rewinding shaft, means for 40 driving the drums and riding roller at different speeds to frictionally engage the coils on the rewinding shaft, means for tilting the rewinding shaft to vary the winding action of the drums and riding roller at opposite 45 ends of the rewound material, and means for tilting the riding roller independently of the rewinding shaft.

50 34. A rewinding machine comprising: two surface rewinding drums, a displaceable rewinding shaft in a plane above and intermediate the drums, a displaceable riding roller above the rewinding shaft, means for driving the drums and riding roller at different speeds to frictionally engage the 55 coils on the rewinding shaft, means for tilting the rewinding shaft to vary the winding action of the drums and riding roller at opposite ends of the rewound material, means for varying the speed of the riding roller, 60 and means for tilting the riding roller independently of the rewinding shaft.

35. A rewinding machine comprising: a pair of surface rewinding drums, a rewinding shaft in a plane above and between said

65 rewinding drums, a riding roller above the rewinding shaft, means for driving the drums and the riding roller and thereby frictionally engaging the material to be rewound on the rewinding shaft, means for disconnecting the riding roller from its 70 driving means and thereby causing it to act as a retarding means and to be frictionally driven by the rewound material, and means for tilting the riding roller independently of the rewinding shaft. 75

36. A rewinding machine comprising: a pair of surface rewinding drums, a rewinding shaft in a plane above and between said rewinding drums, a riding roller above the 80 rewinding shaft, means for driving the drums and the riding roller and thereby frictionally engaging the material to be rewound on the rewinding shaft, means for disconnecting the riding roller from its driving means and thereby causing it to act as a retarding means and to be frictionally driven by the rewound material, means for 85 tilting the rewinding shaft with respect to the axis of the drums and the riding roller, and means for tilting the riding roller independently of the rewinding shaft. 90

37. A rewinding machine comprising: a pair of surface rewinding drums, a rewinding shaft in a plane above and between the rewinding drums, a riding roller above the rewinding shaft, means for manually raising and lowering the riding roller, means for manually raising and lowering the rewinding shaft, means included in the lifting and lowering means of the rewinding shaft for tilting said shaft with respect to the axis of the rewinding drums and the riding roller, and means for tilting the riding roller independently of the rewinding shaft. 100

38. A slitting and rewinding machine comprising: a pair of surface rewinding drums, a rewinding shaft in a plane above the drums and intermediate the same, slitting means beneath the rewinding drums including a positively driven member and a cutter rotating idly in engagement with the member, and transmission mechanism, located wholly at one end of the machine, for driving the drums and the member in the same direction and comprising a gear on each of the drums and on the member, and an intermediate gear in a plane beneath the drums and intermediate the same meshing with all of said other gears. 110

39. A slitting and rewinding machine comprising: a pair of surface rewinding drums, a rewinding shaft in a plane above the drums and intermediate the same, a riding roller in a plane between the drums and above the rewinding shaft, slitting means beneath the rewinding drums including a positively driven member and a cutter rotating idly in engagement with the member, 120

- and transmission mechanism, located wholly at one end of the machine, for driving the drums and the member in the same direction and comprising a gear on each of the drums 5 and on the member, and an intermediate gear in a plane beneath the drums and intermediate the same meshing with all of said other gears, an upright shaft on the same side of the machine as the before mentioned 10 gears extending in a plane intermediate the drums, driving means between the riding roller and said upright shaft, and driving means between the intermediate gear and the upright shaft.
- 15 40. A slitting and rewinding machine comprising: a pair of surface rewinding drums, a rewinding shaft in a plane above the drums and intermediate the same, a riding roller in a plane between the drums and 20 above the rewinding shaft, slitting means beneath the rewinding drums including a positively driven member and a cutter rotating idly in engagement with the member, and transmission mechanism, located wholly 25 at one end of the machine, for driving the drums and the member in the same direction and comprising a gear on each of the drums and on the member, and an intermediate gear in a plane beneath the drums and intermediate the same meshing with all of said 30 other gears, an upright shaft on the same side of the machine as the before mentioned gears extending in a plane intermediate the drums, driving means between the riding roller and said upright shaft, driving means between the intermediate gear and the upright shaft and a slip friction drive included in the last driving means.
- 35 41. A rewinding machine comprising: a pair of surface rewinding drums, a rewinding shaft in a plane above the drums and intermediate the same, a riding roller in a plane between the drums and above the rewinding shaft, and transmission mechanism, located wholly 40 at one end of the machine, for driving the drums and the riding roller in the same direction and comprising a gear on each of the drums, an intermediate gear in a plane beneath the drums and intermediate the same meshing with the drum gears, an upright shaft, on the same side of the machine as the before-mentioned gears, extending in a plane intermediate the drums, driving means between the riding roller and said upright shaft, and driving means between the intermediate gear and the upright shaft.
- 45 42. A rewinding machine comprising: a pair of surface rewinding drums, a rewinding shaft in a plane above the drums and intermediate the same, a riding roller in a plane between the drums and above the rewinding shaft and transmission mechanism, located wholly 50 at one end of the machine for driving the drums and the riding roller in the same direction and comprising a gear on each of the drums, an intermediate gear in a plane beneath the drums and intermediate the same meshing with the drum gears, an upright shaft, on the same side of the machine as the before-mentioned gears, extending in a plane intermediate the drums, driving means between the riding roller and said upright shaft, and driving means between the intermediate gear and the upright shaft.
- 55 43. A slitting and rewinding machine comprising: slitting and rewinding elements, a power unit including transmission means for driving the slitting and rewinding elements and a clutch and a brake all located on one side of the machine, and controlling means for the clutch and brake located on the other side of the machine.
- 60 44. A slitting and rewinding machine comprising: slitting and rewinding elements, a power unit including a clutch and a brake located on one side of the machine, controlling means for the elements of the power unit located on the other side of the machine and two rockshafts extending transversely across the machine from the controlling means to the clutch and brake.
- 65 45. A slitting and rewinding machine comprising: slitting and rewinding elements, a power unit including a clutch and a brake located on one side of the machine, controlling means for the elements of the power unit located on the other side of the machine and two rockshafts extending transversely across the machine from the controlling means to the clutch and brake.
- 70 46. A slitting and rewinding machine comprising: slitting and rewinding elements, a power unit including transmission means for driving the slitting and rewinding elements and a clutch and a brake all located on one side of the machine, controlling means for the clutch and brake located on the other side of the machine and two rockshafts extending transversely across the machine from the controlling means to the clutch and brake.
- 75 47. A slitting and rewinding machine comprising: slitting and rewinding elements, a power unit including transmission means for driving the slitting and rewinding elements and a clutch and a brake all located on one side of the machine, controlling means for the clutch and brake located on the other side of the machine and two rockshafts extending transversely one within the other across the machine from the controlling means to the clutch and brake.
- 80 48. A slitting and rewinding machine comprising: a pair of surface rewinding

- drums, a rewinding shaft in a plane above the drums and intermediate the same, a riding roller in a plane between the drums and above the rewinding shaft, slitting means with the gears on the winding drum shafts, 65 beneath the rewinding drums including a positively driven member and a cutter rotating idly in engagement with the member, and transmission mechanism, located wholly at one end of the machine, for driving the drums and the member in the same direction and comprising a gear on each of the drums and on the member, and an intermediate gear in a plane beneath the drums and intermediate the same meshing with all of said other gears, an upright shaft on the same side of the machine as the before-mentioned gears, extending in a plane intermediate the drums, driving means between the riding roller and said upright shaft, a bevel gear 20 on the upright shaft, a bevel gear on the intermediate shaft in mesh with the first bevel gear, and a slip friction drive between the intermediate gear and the bevel gear on the intermediate shaft. 25 49. A rewinding machine comprising: a pair of surface rewinding drums, a rewinding shaft in a plane above the drums and intermediate the same, a riding roller in a plane between the drums and above the rewinding shaft, and transmission mechanism, located wholly at one end of the machine, for driving the drums and the riding roller in the same direction and comprising a gear on each of the drums, an intermediate gear in a plane beneath the drums and intermediate the same meshing with the drum gears, an upright shaft, on the same side of the machine as the before-mentioned gears, extending in a plane intermediate the drums, 30 driving means between the riding roller and said upright shaft, a bevel gear on the upright shaft, a bevel gear on the intermediate shaft in mesh with the first bevel gear, and a slip friction drive between the intermediate gear and the bevel gear on the intermediate shaft. 35 50. A power unit for winding machines comprising: two winding drum shafts, an intermediate shaft beneath and intermediate the winding drum shafts, a gear on each of the winding drum shafts, a gear on the intermediate shaft in mesh with the gears on the winding drum shafts, an upright shaft for driving a top pressure roll, a bevel gear 40 on the upright shaft, a bevel gear on the intermediate shaft, and a slip friction drive between the intermediate gear and the bevel gear on the intermediate shaft. 45 51. A power unit for slitting and rewinding machines comprising: two winding drum shafts, an intermediate shaft beneath and intermediate the winding drum shafts, a gear on each of the winding drum shafts, a gear on the intermediate shaft in mesh with the gears on the winding drum shafts, an upright shaft for driving the top pressure roll, a bevel gear on the upright shaft, a bevel gear on the intermediate shaft, a slip friction drive between the intermediate gear and the bevel gear on the intermediate shaft, a transmission element, a clutch and a brake pulley all mounted on one of the winding drum shafts, two rock-shafts extending one within the other transversely across the machine, means for actuating the clutch from one of said rock- 50 55 60 65 70 75 80 85 90 95 100 105 110 115 120 125

shafts, a brake element associated with the brake drum, and means for actuating said brake element from the other of said rockshafts.

5 55. A power unit for winding machines comprising: two winding drum shafts, an intermediate shaft beneath and intermediate the winding drum shafts, a gear on each of the winding drum shafts, a gear on the intermediate shaft in mesh with the gears on the winding drum shafts, an upright shaft for driving the top pressure roll, a bevel gear on the upright shaft, a bevel gear on the intermediate shaft, a slip friction drive 10 between the intermediate gear and the bevel gear on the intermediate shaft, a transmission element, a clutch and a brake pulley all mounted on one of the winding drum shafts, two rockshafts extending one within 15 the other transversely across the machine, means for actuating the clutch from one of said rockshafts including: a slideable member on said winding drum shaft and a bell crank for moving the slideable member; a brake 20 element associated with the brake drum, and means for actuating said brake element from the other of said rockshafts.

56. A power unit for winding machines comprising: a main framework for the machine, a supplemental framework independent of and extraneous to the main framework, aligned bearings in the main and supplemental frameworks, an intermediate shaft mounted in said bearings, an intermediate gear on said intermediate shaft, winding drum shafts mounted in the main framework one on each side of and above the intermediate shaft, a gear on each of said winding drum shafts in mesh with the intermediate gear, a shaft for driving the top pressure roll, and means including a slip friction drive for driving said last-mentioned shaft from the intermediate gear.

57. A top pressure roll drive for winding machines including: an intermediate gear, a bevel gear, a slip friction drive between the intermediate and bevel gears, a thrust member rotatable with the intermediate gear and slidably mounted for acting on the slip friction drive, and a non-rotatable thrust member slidably mounted for acting on the rotatable thrust member.

58. A top pressure roll drive for winding machines including: an intermediate gear, a bevel gear, a slip friction drive between the intermediate and bevel gears, a thrust member rotatable with the intermediate gear and slidably mounted for acting on the slip friction drive, and a non-rotatable thrust member slidably mounted for acting on the rotatable member and means for exerting variable spring pressure on the non-rotatable thrust member.

59. A top pressure roll drive for winding

machines including: an intermediate gear, a bevel gear, a slip friction drive between the intermediate and bevel gears, a thrust member rotatable with the intermediate gear and slidably mounted for acting on the slip friction drive; a non-rotatable thrust member slidably mounted for acting on the rotatable thrust member and an antifriction end thrust bearing between the non-rotatable and rotatable thrust members.

60. A top pressure roll drive for winding machines including: an intermediate gear, a bevel gear, a slip friction drive between the intermediate and bevel gears, a thrust member rotatable with the intermediate gear and slidably mounted for acting on the slip friction drive, a non-rotatable thrust member slidably mounted for acting on the rotatable thrust member, and means for exerting variable spring pressure on the non-rotatable thrust member including a pivoted yoke member controlling the non-rotatable thrust member, a threaded stem, and a spring the pressure of which latter against the yoke member is adjustable by means of the threaded stem.

61. A top pressure roll drive for winding machines comprising: an intermediate gear, a bevel gear, friction plates housed within the intermediate gear, alternate friction plates being rotatably connected respectively with the intermediate gear and with the bevel gear, a thrust member rotatable with the intermediate gear and slidably mounted, and thrust rods extending from said rotatable thrust member and projecting through the intermediate gear to act on said friction plates.

62. A top pressure roll drive for winding machines comprising: an intermediate gear, a bevel gear, friction plates housed within the intermediate gear, alternate friction plates being rotatably connected respectively with the intermediate gear and with the bevel gear, a thrust member rotatable with the intermediate gear and slidably mounted, thrust rods extending from said rotatable thrust member and projecting through the intermediate gear to act on said friction plates, and means for exerting variable spring pressure on the rotatable thrust member.

63. A top pressure roll drive for winding machines comprising: an intermediate gear, a bevel gear, friction plates housed within the intermediate gear, alternate friction plates being rotatably connected respectively with the intermediate gear and with the bevel gear, a thrust member rotatable with the intermediate gear and slidably mounted, thrust rods extending from said rotatable thrust member and projecting through the intermediate gear to act on said friction plates and a non-rotatable thrust member

slidably mounted for acting on the rotatable thrust member.

64. A displaceable winding shaft, a displaceable top pressure roll, two concentric handwheels, transmission means including flexible connections between one of said handwheels and the winding shaft, and transmission means including flexible con-

nections between the other handwheel and the top pressure roll.

Signed at New York city, in the borough of Brooklyn, county of Kings and State of New York, this 30th day of November, 1917.

JAMES A. CAMERON.
